HEAD COVERING

Roman John Ernst, Detroit, Mich.

Application July 24, 1941, Serial No. 403,779

4 Claims. (Cl. 2-174)

This invention relates to an improved device for enveloping the human head.

The prevalent use of cosmetics by women has accentuated the losses caused by the soiling of gowns when they are slipped on over the head. Retail stores have suffered great losses due to the prevalent practice whereby prospective customers are permitted to try on clothing before purchase.

Means to prevent this loss have been suggested heretofore. It is the aim of this invention to provide an improved means for preventing this loss and removing the disadvantages inherent in prior head coverings. It is the aim of this invention to provide a head covering or hat made of one piece and which will be able to compensate for any mode of coiffure. It is a further aim of this invention to provide a head covering which is secure on the head and is not subject to movement when a dress is put on or slipped over the head, and it is a further aim to provide a device which may be put on without creating undue stress in the garment. It should be noted that the device is also adapted to prevent the coiffure and make-up of the wearer from being disarranged and to protect the wearer from unpleasant facial contact with dresses that have been tried on or worn before.

It is to be understood that although this device will be referred to herein as a means for preventing the soiling of dresses, this invention is not so limited. It is to be understood that this head covering with slight alterations of material may be used for other purposes, for example, a nurse's hat, a doctor's operating mask, a mosquito netting, a rain hat, shower cap, and for various other purposes.

In the accompanying drawings:

Fig. 1 is a plan view of the contour of the main body of the covering before construction;

Fig. 2 is a plan view of the piece of netting to be used in construction of the head covering;

Fig. 3 is a partial plan view showing the netting of Fig. 2 installed in the body portion of Fig. 1.

Fig. 4 shows the assembly of Fig. 3 when folded upon its vertical center line.

Fig. 5 illustrates the next steps taken in the construction of the head covering.

Fig. 6 is a rear view of the completed head covering.

Fig. 7 is a rear view of the head covering being placed upon the head of a wearer.

Fig. 8 is a profile view of the head covering when worn by a person.

Fig. 9 is a front view of the covering on the head of a wearer.

The construction of the head covering will be first described. It will be noted that Figs. 1 through 6 illustrate the various steps taken in the construction of the device. Referring to Fig. 1, a plan view of the body portion 10 of the device is shown. It is to be understood that this body portion can be made of any suitable flexible material. It is, however, preferred to make it of tissue paper or a like inexpensive material. This permits it to be discarded after one using without prohibitive expense being involved. For sanitary reasons this is, of course, desirable.

15 The body portion 10 is provided with an opening 11. A piece of netting 12, shown in Fig. 2, has substantially the same shape as the opening 11 and is adapted to be retained therein. In the assembled device this netting 12 permits normal respiration and vision. It is preferable to have the netting 12 starched so that the head covering when worn will tend to be spaced slightly from the face of the wearer. In Fig. 3, the netting 12 is shown as covering the opening 11.

20 The netting and body portion are glued or stitched together at 13 around the periphery of the netting. The next step of assembly comprises folding the body portion and netting along the line 4-4 of Fig. 1. The folded assembly is shown in Fig. 4. The dotted line 15 designates a line along which a cut is to be taken to remove superfluous material.

25 The folded halves of the body portion 10 are sewed together along the lines 15, 18 and 19. It is to be understood that while sewing is referred to herein as the fastening means, other means such as adhesive substances could be employed.

Reference to Fig. 5 will show a reinforcing element 20 which extends partially around the bottom periphery of the device. This reinforcing element 20 may be in the form of a hem or fold of additional material glued or sewn around the base of the device substantially on the line 17 of Fig. 4. The dot-dash lines of Fig. 5 show the contour of the device before the folding operations have been preformed. It should be noted that except for the cut along the line 15 of Fig. 4 the external contour of Fig. 4 and the unfolded showing of Fig. 5 are substantially identical.

30 The folding operations comprise folding the point 21 inwardly where it assumes the position designated as 22. This creates a triangular layer 23 on the top of double thickness adapted to retain the shape of the device. Vertical linear folds are made along the lines 24 and a gusset 25 is

created at the lower rear portion of the hat. A sticker 26 or, if preferred, sewing along the base of the triangular top portion of the cover serves to retain the folds substantially in place and the covering device in assembled relation.

In use, the head is inserted through the open bottom portion of the hat and the chin retained in the curved portion 27 formed by the lines 15. The device is then rotated until it assumes a position with the back of the hat at the base of the neck of the wearer. The gusset 25 permits considerable flexibility of the size of the covering device to accommodate coiffures of varying styles. The inverted pleats 28 are formed in the back of the device to adjust it to the contour of the head of the wearer. Tapes 29 fastened to the rear of the device extend upwardly from their fastened portion. The wearer may cross the tapes and will cross them above the base of the hat, as shown in Fig. 7, due to the fact that they extend upwardly from their fastened portion. Tightening the tapes then draws the base of the hat around the wearer's neck. The tapes are then brought forward and tied under the chin, as shown in Figs. 8 and 9. The tapes being adapted to be crossed at the back above the base of the hat do not catch under and draw the lower edge of the gusset 25 upward and as they are crossed they retain the base of the hat firmly against the neck.

It should be noted that the head covering as described herein is retained under the chin so that the application of force upon the tapes does not tend to pull the hat off. In addition, it should be noted that by providing for the tapes to be tied under the chin, it is not necessary to extend the arms to uncomfortable positions as would be necessary to tie it at the back of the neck. This not only prevents discomfort but prevents the tearing of tight dresses. The inverted pleats 28 and gusset 25 permit the device to accommodate a coiffure of any style.

The device is adapted therefore to protect dresses from cosmetics and to serve as a sanitary protection for the wearer from dresses which have been tried on or worn previously. The device also protects the wearer's hair dress and make-up from being disheveled by repeated trying on of dresses.

Retaining the covering under the chin also serves to prevent the device from being removed when a garment is taken off.

What I claim is:

1. A head covering to be worn by a person comprising a flexible body portion having a first and second opening therein and a gusset opposite said second opening, said gusset taking the form of two triangles joined along adjacent sides to form a crease and with their bases forming a part of the edge of said first opening and with the remote sides of said triangles joined to the main body of the covering to form creases, the sides of said triangles converging upwardly toward the top of said head covering, said first opening being adapted to receive the head of said person, a transparent foraminated face portion covering said second opening, two tapes extending in an upward direction from said body portion adjacent said first opening, said tapes being adapted to be crossed and tied and to retain the gusset

adjacent the head of said person and a portion of the covering adjacent the neck of said person.

2. A head covering to be worn by a person comprising a one piece flexible body portion having a first and second opening therein and a gusset opposite said first opening, said gusset taking the form of two triangles joined along adjacent sides to form a crease and with their bases forming a part of the edge of said second opening and with the remote sides of said triangles joined to the main body of the covering to form creases, the sides of said triangles converging upwardly toward the top of said head covering, said gusset being adapted to make the volume of the covering adjustable, said second opening being adapted to receive the head of said person, netting covering said first opening, a triangular top portion of double thickness adapted to retain the shape of said covering and means to retain said covering firmly on the head of said person.

3. A head covering to be worn by a person comprising a flexible body portion having a first and second opening therein and a gusset opposite said first opening, said gusset taking the form of two triangles joined along adjacent sides to form a crease and with their bases forming a part of the edge of said second opening and with the remote sides of said triangles joined to the main body of the covering to form creases, the sides of said triangles converging upwardly toward the top of said head covering, said gusset being adapted to make the volume of the covering adjustable, said second opening being adapted to receive the head of said person, a transparent foraminated face portion covering said first opening, a triangular top portion of double thickness adapted to retain the shape of said covering, said triangular top portion having an apex positioned centrally of and at the front of the top of said head covering and the other two apexes positioned on opposite sides and at the rear of the top of the said head covering, and means to retain said covering firmly on the head of said person.

4. A head covering to be worn by a person comprising a flexible body portion having a first and second opening therein and a gusset opposite said first opening, said gusset taking the form of two triangles joined along adjacent sides to form a crease and with their bases forming a part of the edge of said second opening and with the remote sides of said triangles joined to the main body of the covering to form creases, the sides of said triangles converging upwardly toward the top of said head covering, said gusset being adapted to make the volume of the covering adjustable, said second opening being adapted to receive the head of said person, a transparent foraminated face portion covering said first opening, a triangular top portion of double thickness adapted to retain the shape of said covering, said triangular top portion having an apex positioned centrally of and at the front of the top of said head covering and the other two apexes positioned on opposite sides and at the rear of the top of the said head covering, a fold line in said triangular top portion extending from the forward apex to the rear side of the triangular top opposite said apex, said fold being perpendicular to the said rear side of the triangular top, and means to retain said covering firmly on the head of said person.

ROMAN JOHN ERNST.
